UNITED STATES PATENT OFFICE.

FRANCIS O. BLACKWELL, OF NEW YORK, N. Y., ASSIGNOR TO THE THOMSON-HOUSTON ELECTRIC COMPANY, OF CONNECTICUT.

ELECTRIC-RAILWAY CONTACT.

SPECIFICATION forming part of Letters Patent No. 426,102, dated April 22, 1890.

Application filed July 23, 1889. Serial No. 318,410. (No model.)

To all whom it may concern:

Be it known that I, FRANCIS O. BLACKWELL, a citizen of the United States, residing at New York, in the county of New York and State 5 of New York, have invented certain new and useful Improvements in Electric-Railway Contacts, of which the following is a specification.

My invention relates to contact devices for an electrically-propelled vehicle, by means of 10 which it may be constantly kept in electrical connection with an insulated line-conductor suspended above the roadway. It is illustrated in the accompanying drawings, in which—

15 Figure I is a front elevation of my contact device. Figs. II and III are details of the contact or trolley wheel. Fig. IV is a perspective view of my switch-point. Figs. V and VI are respectively side and front elevations of my 20 contact device applied to a car, and Fig. VII is a detail view illustrating the slotted hollow guide and follower for shifting the contact-wheel.

The principal features of my contact device 25 are, first, that the wheel which runs in contact with the line-wire is journaled upon a transverse guide placed at the end of a rod or similar extension from the vehicle, so that it may have a freedom of lateral movement 30 independent of the rod, and thus accommodate itself to irregularities of the line-wire much more easily than in the present form of the device, wherein the wheel has a fixed bearing on the rod and the rod itself has a 35 pivoted connection with the vehicle, affording the necessary movements relative thereto; secondly, the wheel has supplemental spring-pressed bearings on the transverse rod, which serve to insure a good electrical connection with it, and has also two cords, which 40 serve both to draw the main supporting-rod down and also to adjust the lateral position of the wheel on the guide in putting it in position against the line-wire.

45 In the drawings, A is the contact-maker, herein shown as a hollow trolley-wheel, which is provided inside with two spring-pressed pieces a, which rest on the transverse rod B, upon which the trolley-wheel is journaled, and 50 insure an electrical connection therewith.

The transverse rod or guide B is supported on the outer end of one or more supporting-rods C, which on transverse axes are pivoted to the roof of the vehicle, and are held up against the line-wire by a spring D, as shown 55 in Fig. V. Rod B is hollow and slotted, as shown in Fig. VII, and a traveler E therein has two projections b through the slot, which embrace the wheel A and serve to move it along the rod to any desired position. Each 60 end of the traveler has a cord or wire attached, which extends out through the end of the rod, and the two then reach down to the platform of the vehicle, where they serve for the manipulation of the device both to draw down 65 C and to adjust A laterally, so as to strike the wire, when C is allowed to rise again.

In practice it has been found that the contact device, in order to preserve continuous contact with the line-conductor, must be 70 capable of two movements—one upward and downward toward and away from the conductor in a plane substantially parallel therewith, and the second laterally or transversely across the conductor—and in the contact devices heretofore used these movements have 75 been secured by jointing the supporting rod or pole in such a manner that it is free to swing in either direction. My present invention, however, secures the desired capability 80 of movement for the contact-maker in another way, and it will be observed that the distinctive generic difference resides in the fact that the present contact device consists of two parts or members, one of which is connected to the vehicle in a manner permitting 85 one of the desired movements but not the other, while the second member, being carried upon the first, partakes of its movement, but is capable also of an additional independent 90 movement in the second direction in which, as above pointed out, the contact-maker should be free to travel. Thus in the specific construction shown the rod or supporting extension C will constitute one member of the contact device, and this is capable of the up-and-down movement around its transverse axis, 95 while the contact-maker A is the second member, and this has, in addition to the movement of the rod C, an independent lateral or 100

transverse movement. This same combination of movements, as I am aware, can be secured by other and different constructions, and my claims are intended to cover all such 5 as fairly fall within the spirit of the invention.

In Fig. IV a switch-point adapted to this and to other contact devices is shown. F is the line-wire, and G is a branch therefrom, 10 both being supported by a curved hanger H. The branch wire G is lower than F, and has a spring-pressed switch-point K, with its point resting normally against main line F. As the wheel A approaches the point it rides 15 down upon it, and then follows it to the right and is led off upon wire G, while on the other hand, when the car is moving in the other direction, the point K is forced aside by the wheel, which passes on out from beneath it. 20 What I claim as new, and desire to secure by Letters Patent, is—

1. The combination, in an electric railway, of a suspended line-conductor, an electrically-propelled vehicle, and an intermediate contact device spring-pressed against the under side of the line-conductor, and consisting of 25 two members, one of which is free to move laterally across the conductor and the other vertically toward and away from the conductor, whereby the contact-maker is allowed freedom both of transverse and vertical movement, in order to maintain the traveling engagement with the conductor, as set forth.

2. The combination, in an electric railway, 30 of a suspended line-conductor, an electrically-propelled vehicle, and an intermediate contact device consisting of a rod or support pivoted so as to permit of up-and-down movement relatively to the conductor, and a contact-making piece carried upon the support, and having an independent transverse movement relatively thereto.

3. The combination, in an electric railway, 35 with a suspended line-conductor and an electrically-propelled vehicle, of a contact device consisting of a rod or support extending upward from the vehicle and movable upward and downward toward and away from the conductor, and a contact-making piece carried upon said support, but having an independent lateral movement relatively thereto.

4. The combination, in an electric railway, 40 of a suspended line-conductor, an electrically-propelled vehicle, and an intermediate contact device consisting of an upward-extending rod or support pivoted to the vehicle on

a transverse axis and provided with a transverse guide, and a contact-making piece free to travel along said guide, substantially as set forth. 60

5. The combination, in an electric railway, of a suspended line-conductor, an electrically-propelled vehicle, and a contact device consisting of an upward-supporting extension from the vehicle, and a transversely-traveling grooved contact-wheel thereupon engaging the under side of the conductor. 65

6. In a contact device for electric railways, the combination of a supporting rod or extension and a contact-wheel journaled thereon 70 with a supplementary spring-pressed contact electrically connecting the wheel and its journal, for the purpose set forth.

7. In a contact device for electric railways, the combination of the hollow contact-wheel 75 and the spring-pressed contacts shielded thereby and engaging the journal of the wheel, substantially as set forth.

8. The combination, with a line-conductor and an electrically-propelled vehicle, of an intermediate contact device consisting of an upward extension from the vehicle, and a transversely-traveling contact-piece at its outer end, and an operating-connection extending therefrom to the vehicle, whereby its 85 lateral position may be determined at will.

9. The combination, in an electric railway, of a suspended line-conductor and an electrically-propelled vehicle with a contact device comprising a transverse guide, and a contact-maker free to travel along said guide, and an operating-connection therefor extending to 90 the vehicle for determining the lateral position of the contact-maker, as set forth.

10. The combination, in a contact device 95 for an electric railway, of the movable upward extension from the vehicle, a transversely-traveling contact-piece on its outer end, and a common operating connection for the contact-piece, and the movable extension 100 by which the lateral position of the former and the upright position of the latter are determined.

11. The combination, with the transversely-traveling contact device, of a cord or similar 105 flexible operating-connection extending from each side thereof and leading to the vehicle.

FRANCIS O. BLACKWELL.
